MARGIN ADJUSTMENT GUIDE

Arthur A. Koch, Cleveland, Ohio

Application November 6, 1936, Serial No. 109,484

6 Claims.

(Cl. 33—76)

My invention relates to margin adjustment guides and especially to straight edge adjustment guides for trimming wall paper margins.

An object of my invention is to provide adjustable guides for a straight edge member used in trimming the margin of a sheet of material.

Another object is to provide a guide adapted to hold a straight edge member in a predetermined position.

Another object is to provide a guide adapted to hold a straight edge member in one position for trimming one margin of a sheet of wallpaper and to hold it in another position for trimming another margin of the sheet of wallpaper.

Another object is to provide adjustable means for holding a straight edge member at one predetermined distance from a longitudinal guide member running along a table surface and adjustable means for holding the straight edge member at another predetermined distance from the longitudinal member, each of the adjustable means being adapted to engage the longitudinal member without being re-adjusted.

Another object is to provide a longitudinal member extending along a table surface and adapted to permit a plurality of finger-members to successively engage the longitudinal member and to permit another finger-member to escape engagement with the longitudinal member so that a straight edge member will be held at one distance from the longitudinal member when one of the finger members is in engagement and to hold the straight edge member at another distance from the longitudinal member when another finger member is in engagement with the longitudinal member.

Another object is to provide a block member adapted to be carried by a straight edge member, the block member having a plurality of fingers adjustably clamped thereto for holding the straight edge member at variable positions upon a table surface.

Another object is to provide a device for holding a straight edge member parallel to the side of a table surface.

Another object is to provide a device for use in trimming the margin of a strip of wallpaper along a true line and parallel to the opposite margin of the strip of wallpaper.

Another object is to provide a device for trimming the margins of unequal width of a strip of wallpaper so that the margins of the remaining strip of wallpaper are parallel.

A still further object is to provide a block member adapted to be carried by a straight edge mem-

ber and a finger-member adjustably mounted on the block member for holding the straight edge member at variable positions upon a table surface, the finger member having graduations thereon for adjustably determining its length and the relative position of the straight edge member.

Other objects and a fuller understanding may be had by referring to the accompanying description and claims, taken in conjunction with the accompanying drawing, in which:

Figure 1 is a plan view of a table or bench used in pasting and trimming wall paper with my device in use while trimming one margin of the wall paper;

Figure 2 is a view similar to Figure 1 but in which another margin and of different width is being trimmed from the strip of wallpaper;

Figure 3 is a cross-sectional view taken through the line 3—3 of Figure 2; and

Figure 4 is a perspective view of one of my devices mounted on a straight edge member and carried on a table surface.

In Figures 1 and 2, I show a plan view looking down upon the top of a table or bench used for supporting a strip of wallpaper during its preparation for hanging upon a wall. The table surface 11 is the usual top of the benches used in this work. As the table surface 11 is usually made of wood, I provide a long flat steel plate 12 upon which the cutting operation takes place, so that the blade of the cutter engages the steel plate 12.

A straight edge member 13 is the usual straight edge member used in trimming margins and for similar work. The straight edge member 13 has a longitudinal groove 14 extending along its length upon its upper surface and in this groove 14, the roller cutter 29 is slidably engaged and carried by the straight edge member 13. The roller cutter 29 is of the usual type used in trimming strips of material and is such that when the handle 30 is pressed downwardly and the cutter 29 moved along the straight edge member 13, the wallpaper or other material along the edge of the straight edge member 13 is severed by the blade of the roller cutter 29.

Upon a longitudinal edge of the table surface 11, I have mounted the longitudinal member 15 which is secured to the table surface by screws 50 or other suitable means for holding it securely to the table. The table surface 11 has a slight counter-sink along its longitudinal edge to accommodate the longitudinal member 15 so that the upper surface of the longitudinal member 15

is flush with the top of the table surface 11 as is better illustrated in Figure 3. The longitudinal member 15 has an upwardly projecting portion 16 extending along its length so as to form an upwardly projecting portion along one longitudinal edge of the table surface 11. As the upwardly projecting portion 16 of the longitudinal member 15 is perfectly straight, any member held parallel to it will also be straight upon the table surface 11. Approximate to each end of the longitudinal member 15, I have provided an open space or cut-away portion 17 in the upwardly projecting portion 16 of the longitudinal member 15.

15 Mounted near each end of the straight edge member 13 by means of the screws 20 are the block members 18. Each block member 18 has two longitudinal openings 19 extending through the block member 18. In one of the openings 19, 20 the finger member 24 having a downwardly projecting portion 25 is inserted and slidably engaged therein. In the other opening 19 of each block member 18 the longer finger member 26 having the downwardly projecting portion 27 is 25 inserted and slidably engaged in the block member 18. The shorter finger member 24 and the longer finger member 26 may be slid in the opening 19 of the block member 18 to various positions so that different lengths of the finger members project from the block member 18. After 30 the finger members have been slid to the desired position so that the pre-determined length of the finger members is extended from the block member 18, it is necessary to clamp or otherwise 35 securely engage the finger members to the block member 18. The block member 18 has projecting portions 21 situated over each finger member, which projecting portion has internal threads therein. A thumb screw bolt 22 is threadably engaged in each projecting portion 21 in such a way 40 that by turning of the handle 23 of each thumb screw bolt 22, the end of the thumb screw bolt will clamp the finger member below it when the screw bolt is turned inwardly and will unclamp the finger member below it when the screw bolt 45 is turned outwardly. Therefore, each finger member may be slid or moved relative to each block member upon which it is carried so as to extend a pre-determined distance outwardly from the block member and may be clamped securely 50 in that position. As each finger member is separately clamped, each may be set at a different length from the block member 18 and from the straight edge member 13 upon which the block member 18 is mounted. The projecting portions 55 25 and 27 of the finger members 24 and 26 respectively extend down sufficiently to engage the upwardly projecting portion of the longitudinal member 15. It is seen that when the projecting portion 25 is pushed up into engagement with the longitudinal member that the straight edge member 13 will be held at one distance from the longitudinal member 15 and that when the projecting portion 27 is pushed up into engagement 60 with the longitudinal member that the straight edge member 13 will be held at another distance from the longitudinal member, the said distances depending upon the relative lengths of the finger members 24 and 26 extending out from the block member 18. As the longer of the finger members would otherwise prevent the shorter of the finger members from engaging the longitudinal member, the open spaces 17 have been provided which permit the projecting portion 27 to be 65 moved to a position so that the projecting portion 70

25 may engage the longitudinal member. When it is desired to have the shorter finger member 24 determine the distance between the straight edge member and the longitudinal member, the straight edge member 13 is shifted longitudinally 5 until the projecting portion 27 is opposite the respective open space 17 and is then moved laterally so that each projecting portion 27 is moved through the respective open space 17 to a position where the projecting portion 25 engages the longitudinal member. When it is desired to have the longer finger member 26 determine the distance between the longitudinal member and the straight edge member, then the projecting portion 27 is moved back through the respective open 10 space 17 by laterally moving the straight edge member until the projecting portion 27 is over the table surface 11. By moving the straight edge member slightly longitudinally of the table 11 and then towards the longitudinal member, the 20 projecting portion 27 will then engage the inner side of the longitudinal member, and thus the length of the longer finger member 26 will determine the distance between the longitudinal member and the straight edge member. Therefore, 25 by means of the block member, the two finger members, and the longitudinal member having the open space therein, the straight edge member may be held or guided in a plurality of distances from the longitudinal member without 30 re-setting the lengths of the finger members.

Wallpaper as it comes in the roll usually has two blank or waste margins 33 and 34 extending along the longitudinal edges of the strip of wallpaper 31. These margins are often of different 35 widths and therefore, in trimming off this margin, the straight edge member 13 upon which the cutter 29 is carried must be held in different positions relative to the strip of wallpaper 31. For a wide margin, as margin 34, the straight edge member 40 13 must be held farther back from the edge of the strip of wallpaper than when the narrow margin 33 is being trimmed. In practice, the strip of wallpaper 31 is spread out along the table 11 with its blank surface upwardly and the paste applied to the blank side. The ends of the strip of wallpaper 31 are then brought up together to 45 meet at the point or junction 32 so as to form a folded strip of material or paper with the paste enclosed and the printed part of the paper on 50 the outside. As the paper has been folded double, any inaccuracy or error in cutting the margin off perfectly straight and longitudinally of the strip of paper will be magnified. It is essential 55 that the margins be trimmed off perfectly true so that when the paper is hung upon the walls the adjoining edges of the strips of wallpaper will be perfectly square and parallel throughout their length. Therefore, great care must be exercised in aligning the straight edge member along the 60 strip of wallpaper so that the cutter will trim off a margin of equal width throughout its length. It is also desirable that such proper trimming of the margin be done with a minimum of effort and time so that the various strips of wallpaper 65 may be trimmed and hung in rapid succession without a large number of adjustments, measuring, and shifting of the straight edge member.

All of the rolls of wallpaper of the selected type will have all the margins on one edge of one width 70 and all the margins on the other edge of another width so that margin 33 and margin 34 will be uniformly the same on all the strips of wallpaper on a certain job to be done as having been uniformly printed with margin 33 and margin 34. 75

Figure 1 illustrates the trimming of the wider margin 34 of a strip of wallpaper after having been pasted and folded with its edges meeting at 32. The longer finger members 26 have been set at the same length and extend from the block members 18 at the proper distance. The longer finger members 26 are moved away slightly from the open spaces 17 so that the longer finger members 26 will engage the side of the longitudinal member, thus holding the straight edge member 13 parallel to the longitudinal member 15. The strip of wallpaper 31 has its edge abutting the longitudinal member so that the straight edge member is also parallel with the edge of the strip of wallpaper 31. The length of the longer finger members 26 is such that the straight edge member 13 is held at the proper distance from the edge of the strip of wallpaper and so that the roller cutter 29 cuts off or trims the margin 34 at its proper width which is uniform throughout the length of the margin.

To trim off the narrower margin 33, the strip of wallpaper is swung around on the table surface 11 so that the other longitudinal edge of the strip of wallpaper abuts the longitudinal member as shown in Figure 2. For determining the position of the straight edge member 13 in this operation, the shorter finger members 24 are utilized. In order to bring them into engagement with the longitudinal member without having to unclamp the longer finger members 26, the straight edge member 13 is shifted so that the projecting portion 27 of each longer finger member 26 is moved through the open spaces 17, thus permitting the shorter finger members 24 to engage the longitudinal member. The length of the shorter finger members 24 are similarly set so that the straight edge member 13 is held in proper position upon the wallpaper 31 so that the margin 33 will be trimmed off at the proper width and at a uniform width throughout its length.

Each strip of wallpaper having the same margins 33 and 34 may thus be trimmed without re-setting my guide device so that the trimming may be done rapidly, accurately, and with a minimum of adjustments and effort.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A device for adjustably guiding the position of a straight edge member used in cutting the border portions from a strip of material upon a table surface, comprising, in combination, a straight edge member, a longitudinal member adapted to be mounted to said table and to extend upwardly therefrom so as to form a guide extending along said table surface, said longitudinal member having a pair of open spaces near the ends of the longitudinal member, a pair of block members adapted to be mounted on said straight edge member near the ends of the straight edge member, a pair of finger members slidably carried by each said block member, each said finger member having projecting portions being adapted to engage said longitudinal member, one finger member of each said pair of finger members being adapted to hold the straight edge member at one pre-determined distance from the longitudinal member and the other finger mem-

ber of each said pair of finger members being adapted to hold the straight edge member at another pre-determined distance from the longitudinal member, one finger member of each pair of finger members being adapted to be moved through said open spaces of the longitudinal member so that the other finger member of each said pair of finger members may engage the said longitudinal member, and means for adjustably securing said finger members to said block members so that the distances between the straight edge member and the longitudinal member may be variably determined, the arrangement of the straight edge member, the longitudinal member, and the finger members being such that the border portions of different widths may be cut from said strip of material by the engagement of different finger members of each pair of finger members against the longitudinal member.

2. A device for adjustably guiding the position of a straight edge member upon a strip of material on a table surface, comprising, in combination, a straight edge member, a longitudinal member adapted to be mounted to said table and to extend upwardly therefrom so as to form a guide extending along said table surface, said longitudinal member having a pair of open spaces near the ends thereof, a pair of block members adapted to be mounted on said straight edge member, a pair of finger members slidably carried by each said block member, each said finger member being adapted to engage said longitudinal member, one finger member of each said pair of finger members being adapted to hold the straight edge member at one predetermined distance from the longitudinal member and the other finger member of each said pair of finger members being adapted to be moved through said open spaces of the longitudinal member so that the other finger member of each said pair of finger members may engage the said longitudinal member, and means for adjustably securing said finger members to said block members so that the distances between the straight edge member and the longitudinal member may be variably determined.

3. A device for adjustably guiding the position of a straight edge member upon a strip of material on a table surface, comprising, in combination, a straight edge member, a longitudinal member adapted to extend upwardly from said table surface and to form a guide extending along said table surface, said longitudinal member having cut-away portions approximate to its ends, a pair of clamping members adapted to be carried by the said straight edge member, a pair of finger members carried by each said clamping member, each said finger member being adapted to engage said longitudinal member, one finger member of each said pair of finger members being adapted to hold the straight edge member at one predetermined distance from the longitudinal member and the other finger member of each said pair of finger members being adapted to hold the straight edge member to another predetermined distance from the longitudinal member, one finger member of each pair of finger members being adapted to be moved through the said cut-away portions of the longitudinal member so that the other finger member of each said pair of finger members may engage the said longitudinal member, and means for clamping said

finger members to the clamping members at variable distances from the longitudinal member.

5. The combination of a straight edge member, a block member adapted to be carried by said straight edge member upon a table surface, said table having a guide mounted thereto and extending upwardly from the table surface, a finger member slidably carried by said block member and adapted to engage against said upwardly extending guide on said table surface, and means for clamping said finger member to said block member at a variably determined distance from the said upwardly extending guide so that the said straight edge member is held at variable 10 positions on said table surface.

15. A device for adjustably guiding the position of a straight edge member upon a strip of material on a table, comprising, in combination, a straight edge member, spacing means carried by 20 said straight edge member, guide means carried by, and mounted to, said table and adapted to

engage said spacing means, and means for adjustably securing said spacer means to said straight edge member so that the straight edge member may be variably spaced at predetermined distances relative to the said guide means. 5

6. A device for adjustably guiding the position of a straight edge member upon a table, said table having an edge portion extending along a side thereof, comprising, in combination, a straight edge member adapted to be carried on said table, 10 spacer means carried by, and extending from, said straight edge member, said spacer means being adapted to engage said edge portion of the table and to space the said straight edge member from the said edge portion, and means for adjustably varying the position of said spacer means in respect to the straight edge member so that the straight edge member may be spaced at variable predetermined distances from said 15 edge portion of the table. 20

ARTHUR A. KOCH.
